UNITED STATES PATENT OFFICE.

WILLIAM J. MCFERRAN, OF PIERRE, SOUTH DAKOTA.

POLE CAP.

Application filed April 7, 1924. Serial No. 704,779.

To all whom it may concern:

Be it known that I, WILLIAM J. MCFERRAN, a citizen of the United States, residing at Pierre, in the county of Hughes and State 5 of South Dakota, have invented a new and useful Pole Cap, of which the following is a specification.

This invention relates to wagon pole caps and aims to provide novel means designed 10 to cooperate with the usual neck yoke ring to lock the ring to the pole and eliminate any possibility of the same becoming accidentally displaced.

Another important object of the invention is to provide a device of this character which may be readily and easily moved to its inactive position to permit the removal 15 of the neck yoke supported on the pole.

With the foregoing and other objects in 20 view which will appear as the description proceeds, the invention resides in the combination and arrangement of parts and in the details of construction hereinafter described and claimed, it being understood 25 that changes in the precise embodiment of the invention herein disclosed, may be made within the scope of what is claimed, without departing from the spirit of the invention.

Referring to the drawing:

30 Figure 1 is a fragmental elevational view disclosing a pole supplied with a cap constructed in accordance with the invention.

Figure 2 is a sectional view taken on line 2-2 of Figure 1.

35 Figure 3 is a sectional view taken on line 3-3 of Figure 1.

Referring to the drawing in detail, the reference character 5 designates a pole tip which is of the usual construction.

40 The cap forming the essence of this invention is indicated generally by the reference character 6 and comprises a length of metal positioned over the tip of the pole, and secured thereto as by means of the 45 curing members 7 and 8.

The lower portion of the cap is curved upwardly as at 9 so that the forward portion thereof will be guarded should the pole move over the ground surface on which the 50 same may be resting.

An offset portion 10 forms a part of the cap and defines a shoulder 11 adapted to be engaged by the neck yoke ring shown in dotted lines in Figure 1 of the drawing and 55 indicated at 12, so that the animals which may be hitched to the neck yoke, may effi-

ciently hold back the wagon of which the pole 5 forms a part.

The forward end of the cap is spaced from the forward end of the pole 5 as at 60 13, the edges of the cap being rounded so that the usual ring employed for connecting a pair of draft animals to the pole will not be cut by the sharp edges of the cap. Forming a part of the cap is an upwardly and 65 rearwardly extended portion 14 formed by bending a portion of the length of metal of which the cap is formed upon itself, the offset portion being curved rearwardly to provide a hook while the space between the 70 overlapping portions of the offset portion 14 will act as a keeper to hold the securing ring 15.

The securing ring is formed preferably of 75 a length of metal bent in a manner to provide a construction as shown by Figure 2, the ends of the length of metal being disposed in spaced relation with each other and twisted laterally providing locking fingers 80 16 adapted to move within the space between the overlapping sections of the offset portion 14 and bite thereinto to insure against movement of the locking ring 15 when moved to its locked position.

In order that the pressure of the side 85 members of the ring 15 will set up a binding action between the ring and edges of the hook member, the hook member is formed with inclined side edges 17 having depressed portions 18 forming rests for the side members of the ring member 15 as clearly shown 90 by Figure 2 of the drawing. Thus it will be seen that in order to move the ring 15 to its inactive position, or to the position as shown in dotted lines in Figure 1 of the 95 drawings, it is necessary to force the ring member upwardly against the binding action between the ring and hook member.

From the foregoing it will be obvious that due to this construction, the ring member 12 100 will be held against accidental displacement from the wagon pole when the ring member 15 is moved to its active position.

I claim:

1. A pole cap including a lower offset portion defining a shoulder to be engaged by a ring member of a neck yoke, an offset portion formed along the upper edge of the cap to provide a hook member, and formed by bending portions of the cap upon itself, 110 a locking link disposed between the portions of the hook member, means for setting

- up a binding action between the hook member and link member, and said link member adapted to provide an abutment for a neck yoke ring supported on the cap.
5. 2. A pole cap including a lower offset portion defining a shoulder to be engaged by a neck yoke ring, a hook member, a securing ring carried by the hook member and adapted to provide an abutment for the 10 neck yoke ring supported on the pole cap, said hook member having its side edges cut away, said ring member having its ends disposed in spaced relation with each other and adapted to frictionally engage the side 15 edges of the hook member to set up a binding action, and fingers carried by the ring member and adapted to bite into the hook member.
3. A pole cap including a lower offset 20 portion, an upper offset portion curved rearwardly to provide a hook member, said hook member being formed by bending a portion of the cap upon itself, said ring member
- adapted to be positioned between the portions of the hook member bent upon itself 25 and said ring member having laterally extended portions adapted to bite into the hook member and restrict movement thereof.
4. A pole cap including a lower offset portion and an upper offset portion curved 30 rearwardly, a locking member pivotally connected with the upper offset portion and adapted to lock a yoke ring on the pole, said pole cap having a forward upwardly curved portion to guide the pole supplied with the 35 cap over the ground surface, and said locking member having means to restrict movement thereof.
- In testimony that I claim the foregoing as my own, I have hereto affixed my signature 40 in the presence of two witnesses.

WILLIAM J. McFERRAN.
